CARBURETOR

Filed May 10, 1926

UNITED STATES PATENT OFFICE

AGUSTIN PARIENTE DE LA CRUZ, OF MADRID, SPAIN

CARBURETOR

Application filed May 10, 1926, Serial No. 108,102, and in France April 7, 1926.

The present invention relates to carburetors formed by a group of small elementary carburetors each comprising an air passage or diffuser in which terminates a connection supplying the carburant.

According to this invention, the discharge openings of the elementary carburetors open into a chamber which communicates with the suction manifold of the motor through a passage having a constant cross section.

When the engine of an automobile is supplied by a carburetor made according to this invention, it is found that it is rarely necessary to have recourse to the change-speed mechanism, the intervention of the latter becoming necessary only at starting and on steep hills, even with an engine of which the cylinders are of moderate cubic capacity. In other cases, the adjustment of the carburetor is sufficient to cause the power developed by the engine, as well as its speed, to vary very progressively in the degree desired.

The annexed drawings show, by way of examples, forms of constructing the carburetor according to this invention.

Figure 1 is a diagram. Figure 2 relates to a form of particular construction which is represented diagrammatically in perspective. Figure 3 is a similar view of a modification. Figure 4 shows in longitudinal section, the details of this modification.

As shown in the diagram of Figure 1, the diffuser is composed of a series of pipes or passages 1. Each of them is provided with a nozzle-tube 2 supplied with liquid fuel by a constant-level device (not illustrated). The air enters into the pipes or passages 1 at their lower ends and passes out from them at their tops which deliver into a collector 3 connected with the induction pipe of the engine.

The openings of all the air-inlets can be simultaneously regulated in the same degree by a suitable closing device 4. As regards the opening of the outlets, it is controlled by another closing device 5 operating in such a manner that one of these outlets is partly opened when another has just been fully opened.

Preferably the pipes 1 are grouped in a

circle; they are for example drilled in a block, the arrangement of which thus resembles that of the barrel of a revolver. Modifications of this kind are shown in Figures 2 and 3.

In the first modification, the fuel is kept at a constant level in a casing 6 which surrounds the perforated block 1a. This block is provided at its periphery with as many grooves such as 6b as there are pipes or 60 passages 1, and it is engaged in a sheath 6a. Each groove thus forms a passage which opens at its base into the casing 6 and such passage is put into communication with one of the pipes 1 by a perforation 6c in the block. The adjustment of the openings for the entrance of air is obtained by a movement of rotation imparted to a disc 7 placed against the corresponding base of the barrel-block. This disc is pierced with holes in number 70 equal to that of the pipes 1—1 and similarly arranged. The result is that, according to its position, the disc masks or uncovers more or less completely these inlets. The control of the disc is effected by a stud 7a and a lever 75 8 connected by any suitable means, for example, to a control-handle mounted upon the steering wheel.

The outlets of one half the pipes 1, deliver from the upper face of the block 1a; the others deliver from the side face of this block, towards its upper part. These two sets of outlets are controlled by a revoluble closing cap 9 having two slotted apertures 9a—9b which commence to uncover one of the outlets of one series when one outlet of the other series has just been fully opened. The closing cap 9 is mounted on an axis 10 which passes through the apparatus from top to bottom and is provided at its base with a controlling crank 11 the operation of which is effected, for example, like that of the lever 8. The slow-running setting is obtained in one of the extreme positions of this closing-cap, 95 at which position a single one of the outlets is partly opened.

Below the lateral outlets, the block is formed with a screw thread to which can be screwed a union (not shown) connecting the 100

carburetor with the induction pipe of the engine.

According to the modification shown in Figures 3 and 4, the outlets 12 from the pipes or passages 1 deliver at the periphery of the block between the two extremities thereof. These outlets form two series arranged at different levels. Their opening is effected by a sleeve 13 provided with a ring 14 for its operation and having a stop pin 13a which limits the movement of the sleeve. This sleeve is provided with apertures such as 13b each corresponding with a series of outlets. The liquid fuel is supplied along the axis of the block by a central passage in the removable stem 15. This passage is branched out very near its commencement into narrow passages each leading to a nozzle 16 (Figure 4) arranged opposite the outlet from one of the pipes or passages 1.

These last mentioned are open to the atmosphere first at the lower end of the block and secondly at the periphery of the upper part of the block. The opening of all the upper outlets is simultaneously adjustable by the operation of a revoluble cap 17, having the necessary apertures. A retaining member 18 screwed to the top of the central removable stem 15 bears by means of a spring 19 and through the cap 17, upon the whole of the block in such a way as to maintain it in place in the casing 20 of the carburetor.

The stem 15 can be easily taken out from the barrel-block in such a way that the clearing (when necessary) of the inlets for the feed of fuel can be effected without difficulty.

What I claim is:

1. In a carburetor of the type comprising means forming a plurality of air passages with a nozzle in each of them for introducing the liquid fuel, means forming air passages with inlet ports at each end, and an outlet port in the middle part and a fuel nozzle in the axis of said outlet port.
2. In a carburetor of the type comprising means forming several air passages with a nozzle in each of them for introducing the liquid fuel, a constant level chamber, a cylindrical body, air passages drilled in the said body around an axial perforation of the same, a plug in said axial perforation, longitudinal ducts into the said plug adapted for supplying the fuel to the nozzles and connected together under the level of the fuel in the constant level chamber.

In testimony whereof I have signed my name to this specification.

AGUSTIN PARIENTE DE LA CRUZ.
